CLAIM

The ornamental design for a burial casket cap panel and dish, as shown and described.

DESCRIPTION

FIG. 1 is a perspective view of our new, original and ornamental design for a burial casket cap panel and dish; FIG. 2 is a front view thereof;

FIG. 3 is a side view thereof, the other side view being a mirror image thereof;

FIG. 4 is a top view thereof, the bottom being a mirror image thereof;

FIG. 5 is a rear view thereof; and

FIG. 6 is a cross-sectional view thereof, taken along line 6—6 in FIG. 2.

The broken line showing of the casket in FIG. 1 is for illustrative purposes only and forms no part of the claimed design.
